(57) CLAIM

The ornamental design for a handbag, as shown and described.

DESCRIPTION

FIG. 1 is a left front perspective view of a handbag of my present invention.

FIG. 2 is a right rear perspective view thereof.

FIG. 3 front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The short dashed broken lines show portions of the handbag that form no part of the claimed design. The long dashed broken lines show stitching, and are included in the claimed design. The claimed surfaces are lined for contour.

1 Claim, 7 Drawing Sheets
